UNITED STATES PATENT OFFICE.

WILLIAM F. WAITE, OF PALMER, MASSACHUSETTS, ASSIGNOR TO WILBUR F. YOUNG, OF SPRINGFIELD, MASSACHUSETTS.

HOOF-PAD RETAINER.

SPECIFICATION forming part of Letters Patent No. 660,536, dated October 23, 1900.

Application filed July 28, 1900. Serial No. 25,117. (No model.)

To all whom it may concern:

Be it known that I, WILLIAM F. WAITE, a citizen of the United States of America, and a resident of Palmer, in the county of Hampden and State of Massachusetts, have invented 5 certain new and useful Improvements in Hoof-Pad Retainers, of which the following is a full, clear, and exact description.

My invention relates to an improvement in 10 hoof-pad holders, and has for its object a very simple, cheap, and efficient retainer for holding the pad in contact with the horse's foot and which retainer can be readily applied to the pad and removed at will.

15 My invention consists in a **U**-shaped wire which has its two ends turned outwardly to catch under the inner edges of the shoe and its central portion turned upwardly at substantially a right angle, so as to hold the rear 20 end of the pad in contact with the heel of the horse's hoof, combined with a **W**-shaped wire which not only serves to hold the pad in position, but to retain the other wire securely in place.

25 Heretofore pad-retaining devices have been formed of two separate pieces of wire, but both of them have been attached to the pad so as to form practically a part thereof, thus requiring a pad of such heavy and tough material 30 that the wire can be fastened securely thereto; but never before have hoof-pad retainers been formed of two separate pieces of wire which are not only separate from each other, but entirely separate from the pad, 35 thus allowing pads of different materials to be used whenever so desired.

In the accompanying drawings, Figure 1 is 40 a perspective showing a hoof-pad retainer which embodies my invention applied directly to the hoof. Fig. 2 is a perspective of the pad-retainer alone.

A represents a horse's hoof shod with the usual shoe, and B the pad which is applied to the bottom of the hoof, and which pad is 45 made of any suitable material and sufficiently long to project beyond the heel of the hoof and to be turned upwardly against the heel. The pad will be made of hair, felt, or any suitable material that may be preferred, and 50 by being made long enough to turn up against the heel the moisture is applied to the heel as

well as to the sole of the foot and keeps the foot thoroughly cool and moist. For the purpose of retaining this pad in contact with the foot two entirely-separate pieces of wire are 55 used, one of which, C, is substantially the shape of the letter **W**, while the other, D, is made **U**-shaped, and neither one is connected to or attached to the pad in any manner. This permits the pad to be of any light material 60 that may be preferred and which may be changed from time to time, as is desired. The **U**-shaped wire or retaining device has its ends G turned outwardly, so as to catch under the opposite inside edges of the shoe, while its 65 central portion is turned at substantially a right angle, as shown at I, for the purpose of holding the end of the pad against the heel of the foot. This **U**-shaped retainer extends forwardly to a point beyond the center of the 70 hoof and by bearing against the turned-up part and against the bottom of the pad near each edge retains the pad in position. In order to retain the pad in contact with the toe of the hoof, the **W**-shaped wire C is also used 75 and which is made to catch over and under the wire D, as shown, and has its two ends to catch under the inside edge of the front of the shoe, as shown. This part C of the retainer serves not only to assist in holding the 80 pad in place at its front end, but also to lock the **U**-shaped part D in position. The two parts of the retainer, which, as above stated, are made entirely separate and distinct from the pad and from each other, retain the pad 85 in position at all times without the slightest fear of its dropping out. The two parts of the retainer, which are made separate and distinct from each other, can be made from any piece of wire which has sufficient elasticity 90 to assist in holding them in place, and while the ends of both pieces are here shown flattened this is not absolutely necessary.

Having thus described my invention, I claim—

1. In a hoof-pad retainer, the pad, combined with the **U**-shaped part of the retainer having its ends turned outwardly to catch under the inside edges of the shoe, and having its middle portion turned upwardly at substantially a right angle to hold the pad in contact with the heel, and the **W**-shaped part

which catches both under and over the **U**-shaped part, and has its front ends to catch under the inside edge of the front of the shoe; the two parts of the retainer being made entirely separate from the pad and from each other, as shown and described.

2. In a hoof-pad retainer, the shoe, and the pad applied to the foot between the edges of the shoe, combined with the **U**-shaped part of the retainer having its ends flattened and turned outwardly to catch under the inner

edges of the shoe, and the **W**-shaped part which catches both under and over the **U**-shaped part and has its flattened ends to catch under the inner edge of the front of the shoe, substantially as set forth.

Signed by me at Springfield, Massachusetts, this 22d day of June, 1900.

WILLIAM F. WAITE.
